UNITED STATES PATENT OFFICE

ELIGIO RUBINI AND JOHN DE LAI, OF TORONTO, ONTARIO, CANADA

ELECTRIC HEATING APPARATUS

Application filed December 3, 1930. Serial No. 499,708.

The invention relates to improvements in electric heating apparatus as described in the present specification and shown in the accompanying drawings that form a part of the same.

One object of the invention is to provide an electrically operated furnace of simple construction, particularly adapted for domestic use and whereby the discomforts and disadvantages of heating apparatus employing oil, coal, gas, or other form of fuel are displaced by the advantages of electrically generated heat.

A further object of the invention is to provide an electric furnace having a low current consumption and which may be readily controlled to provide the required degree of heat at the minimum of cost.

Another object is to provide an efficient circulatory system whereby clean air is fed to the heating chamber and passed on in an almost continuous flow to the outlet pipes and thence to the registers, thereby preventing stagnation of the heated air within the furnace and insuring the maximum flow of air to the rooms.

Another object is the convenient arrangement of parts whereby access may be easily had to the elements in the event of the desire to remove, or replace same.

A still further object is to provide simple and efficient apparatus which may be readily transformed into a ventilating means capable of supplying cool, fresh air to the rooms of a building during any period when heat is not required.

And generally the objects of the invention are to provide an efficient electric furnace, of few parts, which may be constructed at reasonable cost, and maintained at a minimum of expense.

The invention consists in the novel features of construction, arrangements and combinations described in the present specification and more particularly pointed out in the claims for novelty following.

In the drawings Figure 1 is a central vertical sectional view through our improved electric furnace.

Figure 2 is a plan view of the structure shown in Figure 1.

Figure 3 is a cross sectional view taken on the line 3—3 of Figure 1.

Figure 4 is a cross sectional view taken on the line 4—4 of Figure 1. 55

Figure 5 is a cross sectional view taken on the line 5—5 of Figure 1.

Figure 6 is a cross sectional view taken on the line 6—6 of Figure 1. 60

Figure 7 is an enlarged horizontal sectional view through a portion of the furnace wall and the air regulator.

Figure 8 is a vertical sectional view taken on the line 8—8 of Figure 7. 65

Figure 9 is a side elevation, partly in vertical section, of a modified form of furnace.

Like numerals of reference indicate corresponding parts in the various figures.

Referring to the drawings, A is the furnace which may be constructed of cast metal, or of any suitable material, and which is shown in the drawings as consisting of three sections, 1, 2 and 3 respectively, although of course said furnace may be constructed in one, or in a plurality of sections without departing from the spirit of the invention. 70

The section 1 which constitutes the base is provided with an air inlet 4 in communication with the outlet 5 of a fan casing 6 in which latter is mounted a fan 7, which fan may be driven in any suitable manner (driving means not being shown in the drawings as same does not constitute a feature of the present invention) and is adapted to cause a flow of air into the air chamber formed within the section 1. 75

Electric element sockets 8 are arranged at intervals around the inner circumference of the intermediate annular section 2 and constitute supports for the elements 9 which screw thereinto, said sockets being constructed of insulating material and preferably being extended through the wall of the furnace section 2 and each having negative and positive wires, indicated by the numerals 10 and 11 respectively, leading to a suitable switch, 11^a or switches, the construction of which is not shown in the drawings as same may be 80

of any suitable design to meet the requirements.

- The top section 3 which fits over the section 2 is preferably concaved to provide an interior positioned inverted cone shaped deflecting wall 12 adapted to deflect the upwardly flowing current of air into the outlets 13 radially arranged in relation thereto and connecting with the pipes to the various rooms.
- 10 The section 3 is provided with a suitable door 14, preferably having a transparent insert 15 therein, said door being arranged at such an angle in relation to the furnace wall that the elements 9 can be seen therethrough and also that anyone wishing to remove, or replace, one or more of such elements can easily reach same through said door.
- 15 A hot water coil 16 may be positioned within the section 3 if so desired and provided with an outlet pipe 17 leading through the furnace wall.

20 The wall of the section 3 preferably carries a water container 18 fillable from the outer side of said wall and opening into the interior 25 of the furnace to give the warm air the desired degree of humidity.

In order to lessen the force of the air reaching the heating elements and to effectually atomize said air an adjustable air filter is positioned within the furnace between the air inlet 4 and the said elements, such filter comprising a perforated disc 19 permanently secured across the furnace and a secondary perforated disc, or plate 20 slidable over the first 35 mentioned disc and according to the positions of said discs in relation to each other controlling the amount of air passing upwardly therethrough.

The horizontal movement of the plate 20 40 is effected by means of a screw 21, threading through a bracket 22 carried by said plate and extending outwardly through the wall of the furnace and through a suitable bracket 23 secured on the outer wall of the furnace and 45 preferably being provided with a knurled head 24.

A perforated disc 25 is also placed across the interior of the furnace above the heating elements so as to further break up the warm 50 air before it enters the pipes, said disc 25 along with the discs 19 and 20 also serving to retain the heat therebetween and thereby provide a heating chamber having a perforated top and bottom.

55 In Figure 9 a modified form of construction is shown in which the air is forced by the fan into a pipe, or coil, 26 positioned within the furnace and is warmed in passing through said pipe before being emitted 60 through a suitable outlet 27 into the body of the furnace for heating by the elements 9.

It is preferable that the air admitted to the furnace be clean, especially when the apparatus is being used as a ventilating medium and 65 to this end a pipe leading from the outside

of the building may be provided with a suitable fitting 28 adapted to be secured over the inlet to the fan.

In practice all of the elements 9 may be under the control of a single switch, or more 70 than one switch may be employed, each controlling the desired number of elements so that the number of elements to be used may be determined by the heat required, also switches designed to regulate the amount of 75 current to each element may be employed. In this manner any desired degree of heat may be obtained.

While the preferred embodiment of our invention has been here shown and described 80 it is of course to be understood that alterations in details of construction and arrangement of parts as come within the scope of the claims for novelty may be made.

What we claim is:—

1. In an electric furnace, the combination with a casing having an air inlet and outlets arranged at opposite ends respectively thereof and means for forcing air through said casing, of an intermediate heating chamber, 90 said chamber comprising a pair of reticulated walls transversely arranged in spaced relation to each other between said inlet and outlets, and a plurality of heating elements removably supported around the inner face 95 of said casing within said heating chamber.

2. In an electric furnace, the combination with a casing having an air inlet and outlets arranged at opposite ends respectively thereof and means for forcing air through said 100 casing, of an intermediate heating chamber comprising a pair of reticulated walls transversely arranged in spaced relation to each other between said inlet and outlets, a plurality of heating elements removably supported around the inner face of said casing within said heating chamber, and operating means in relation with one of said reticulated walls extending through the wall of said casing to control the flow of air to said heating 110 chamber.

Signed at Toronto, Ontario, this 7th day of November, 1930.

ELIGIO RUBINI.
JOHN DE LAI.
